UNITED STATES PATENT OFFICE.

JOHN J. CRALL, OF CHAUNCEY, MISSOURI.

BOILER-CLEANER.

SPECIFICATION forming part of Letters Patent No. 610,703, dated September 13, 1898.

Application filed December 3, 1897. Serial No. 660,657. (No model.)

To all whom it may concern:

Be it known that I, JOHN J. CRALL, residing at Chauncey, in the county of Camden and State of Missouri, have invented a new 5 and useful Boiler-Cleaner, of which the following is a specification.

This invention relates to improvements in steam-boiler cleaners, and has for its object to provide means in permanent attachment 10 with a boiler whereby the dirt, calcined accumulations, scales, or other deposits within the lower portion of the boiler may be scraped off and blown from the same, which operation may be effected at any time, even when the 15 boiler is in use with considerable pressure exerted.

My improved device provides a convenient and inexpensive attachment, simple in operation and not likely to get out of order and 20 which may be constructed with the boiler in process of manufacture or applied at very moderate expense to existing boilers.

In the drawings herewith, forming part of this specification, in which like parts are designated by similar letters of reference, Figure 25 1 is a side elevation of a boiler equipped with my improved cleaner, a portion of the cover being broken away. Fig. 2 is a side elevation of the cleaner, partly in section, and the end 30 wall of the boiler, also in section. Fig. 3 is an end elevation of the scraper or brush hereinafter described. Fig. 4 is a side elevation of my complete cleaner, showing manner of its attachment to the end wall of boiler, the latter 35 being in vertical section. Fig. 5 is a longitudinal section of that shown in Fig. 4, with an additional outer connection and with globe-valve, the additional portion being in side elevation. Figs. 6, 7, and 8 are perspective 40 details of my invention, hereinafter fully described.

In the construction of my improved boiler-cleaner I provide first a stuffing-box nipple A, provided with a screw-threaded portion B, 45 adapted to register with a screw-threaded aperture through the mud-head C' of the boiler C, the said mud-head being located adjacent to the bottom portion of the boiler. Upon the said nipple A, within the boiler C and bearing 50 closely against the inner surface of the boiler, I provide an annular shoulder D, said shoulder being provided with inwardly-projected

slotted catch-lugs E and E'. The outer end of said nipple A is screw-threaded, as shown, and is also provided intermediately with a 55 cock F.

I next provide a sliding sleeve consisting of an inner section G and outer section G', the meeting ends being screw-threaded, so as to be securely joined together, presenting when 60 so joined an even circumferential surface. Adjacent to the inner end of the section G, I provide an annular shoulder G² and beyond said shoulder an inner screw-threaded end G³. Adjacent to the outer end of section G', I pro- 65 vide a globe or other valve G⁴, and beyond said valve I provide a screw-threaded end G⁵.

Adapted for attachment to the screw-threaded end G³ of the sleeve-section G, I provide a sliding valve-block H, said valve-block 70 provided with an upwardly-curved recess of the same diameter as the said sleeve-sections G and G'. Upon the bottom of said block H, I provide a plate H', secured by means of binding-screws H² in such a position as to permit 75 the action of a gate-valve H³, the aperture of said valve being of the same diameter as the inner diameter of sleeves G and G'. Upon the outer end of said gate-valve H³, I provide a catch-head H⁴. 80

Screw-threaded into the aperture in plate H', I provide a depending tube K, which at its lower end is screw-threaded into a recessed sliding foot K'.

Extending through the wall of section G of 85 the sliding sleeve I provide an aperture F', which is in alignment with the inner end of the cock F and registers therewith when said sliding section G has been drawn outwardly as far as the shoulder G² will allow. Upon 90 the periphery of said shoulder G², I provide a beveled lug I, which by means of its engagement with the slotted lug E of shoulder D holds section G in its place.

I next provide a brush-head L, adapted to 95 be secured upon the inner end of the sliding valve-block H by means of the binding-screw L', passing through said brush-head and a washer L² into the sliding valve-block H. Depending from said brush-head I provide a 100 wire brush M, its lower edge being of the same curvature as the inner surface of the boiler C.

I next provide upon the shoulder G² a bevelled lug I, as shown in Fig. 7. The purpose

of said lug is to secure the end sleeve-section G to the nipple A by being engaged by the slotted lug E, projecting from the shoulder D of the nipple A. The parts having been 5 constructed as herein described, the operation of my device is as follows:

The stuffing-box nipple A having been securely fastened within the mud-head C' and the sleeve-section G projected therethrough, 10 the section G' is connected with said section G, the valve-block H in the interior of the boiler C being in screw-threaded connection with the inner end of said section G.

The valve H³ when opened by being drawn 15 out will stay open until the head H⁴ comes in contact with the shoulder D on the nipple A. The valve H³ is opened by rotating the head H to the left to connect the head H⁴ with the slotted lug E'. The section G must be pressed 20 until everything stops, as it must, as the valve can only move a limited distance, and then the section G must be rotated in the opposite direction, which will disconnect the head H⁴ from the lug E', the foot K being in a vertical 25 position. The valve G⁴ is now opened and the cleaner reciprocated in and out, the blowing continuing during this operation, blowing out the matter stirred up by the comb-teeth M.

To reciprocate the cleaner, the section G' is 30 grasped by the hands, rags or like protection being used, or may be clamped by wooden jaws or in a hand-vise.

In order to provide means for discharging the water and steam remaining in the sections G and G', I provide a supplemental cock F, through which such discharges may be made to occur after the valve H³ is closed. The aperture F' in the sleeve G will register with the cock F when the shoulder G² meets 35 the inner end of the nipple A. In such position the section G' may be removed and the cap N applied, as shown in Fig. 2, said cap being provided with screw-threads engaging the outer screw-threaded surface of the nipple A for the purpose of preventing any leakage should the gate-valve H³ or shoulder G² fail to fit steam-tight on the end of the nipple A. An ordinary stuffing-box A' is provided, as shown, to make a steam-tight joint 40 between nipple A and sections G G'. The outer end of the section G', beyond the globe-valve G⁴, is screw-threaded in order to permit the attachment of a conducting pipe or hose, if desired.

55 In Fig. 6 I have reproduced in detail the nipple A. In Fig. 7 is shown a detail view of the sleeve G, and in Fig. 8 is shown a detail view of the gate-valve H³.

The brush-head L is not bound rigidly upon 60 the valve-block H, but oscillates freely thereon in order that said valve-block and the foot K' may be rotated without rotating said brush-head, as it would be impossible, owing to the length of the brush, to rotate the same 65 within the boiler, the lower end of the brush coming into contact with the bottom of the boiler. I do not confine myself to the brush

herein described, but may substitute therefor a solid scraper-plate or any other species of scraper or brush to effect the same purpose.

One of the chief advantages found in my device is that the communication with the interior of the boiler may be at any time cut off by the operation of the valve H³ without depending upon the exterior valve, the said action being effected by the same drawing outwardly of the said section G', after which said section is rotated until the valve-head H⁴ has been gripped by the slotted lug E'. When 80 the blow-out is thus terminated and the water and steam exhausted through the cock F, the section G' will soon cool, so as to permit its detachment from section G, after which the cap M is applied. Another advantage of 85 my device is found in the fact it has no small delicate parts liable to become detached within or without the boiler, and on this account it will be found to be exceedingly durable, as well as effectual.

Having thus described my invention, what I claim as new, and desire to secure by means of Letters Patent, is—

1. The combination with a steam-boiler cleaner, of a valve-block, a sliding foot secured thereto, a brush-head loosely pivoted thereon, a depending brush or scraper secured to said head, a gate-valve operating longitudinally upon said block between the bottom of same and a retaining-plate, a nipple screw-threaded through the mud-head of the boiler, said nipple being provided with an outer screw-threaded end and an inner shoulder, a sliding tubular sleeve projected through said nipple having its inner end exteriorly and its outer end interiorly screw-threaded and provided with a shoulder next the inner end, a catch-head upon said gate-valve adapted to be engaged by a slotted lug upon the annular shoulder of said nipple, a beveled lug upon the shoulder of the said sliding sleeve adapted to be engaged by another slotted lug upon the shoulder of said nipple, an outer sleeve having both its ends screw-threaded and adapted for attachment to said first-mentioned sleeve, a valve intercepting said outer sleeve, and a supplemental valve or cock in said nipple adapted to register with an aperture in the inner or first-mentioned sliding sleeve when the same is in its most outwardly-drawn position, all substantially as herein shown and set forth.

2. The combination with a steam-boiler, of a cleaner therefor, consisting of a nipple screw-threaded through the mud-head of the boiler, a sliding tubular sleeve projected through said nipple, an annular shoulder adjacent to the inner end thereof, a screw-threaded inner end having secured thereto a valve-block, a gate-valve secured within said block provided with a catch-head, a slotted lug projected from the inner portion of said nipple adapted to engage the catch-head of said valve when the said valve-block is ro-

tated by means of the outwardly-projected sleeve, a beveled lug formed upon the periphery of the annular shoulder of said sleeve adapted to be engaged by another slotted lug 5 on the inner portion of the said nipple, whereby the valve-block is locked in an abutting position against the inner end of the nipple, a recessed sliding foot secured to said valve-block, an oscillating brush-head also secured 10 upon the inner end of said block, a depending brush, an outer screw-threaded tubular sleeve in connection with that first herein mentioned, a globe or other valve intercepting the same adjacent to its outer screw-threaded end, and 15 an auxiliary exhaust-cock leading through said nipple adapted to register with an aperture in the first-mentioned sliding sleeve when the same is in its most outwardly-drawn position, the whole constructed, arranged, and 20 adapted for operation substantially as herein shown and set forth.

3. The combination with a steam-boiler, of a cleaning device therefor, consisting of a nipple A, projected through a head C, a sliding sleeve G, a valve-block H secured thereon, 25 a gate-valve H³, an oscillating brush-head L, a brush or scraper M, means as shown for operating said valve consisting of catch-head H⁴ coacting with slotted lug E', means for securing said valve-block and nipple together 30 consisting of lug I coacting with slotted lug E, an outer sleeve G', a globe-valve G⁴, an exhaust-cock F adapted to register with an aperture F' when said sleeve G is in a certain position, the whole constructed, arranged, and 35 adapted to operate substantially as and for the purpose herein set forth.
